AUTOMATIC SAFETY DEVICE FOR POTTERY MACHINES

Original Filed March 9, 1927 2 Sheets-Sheet 2

Patented May 13, 1930

1,758,084

UNITED STATES PATENT OFFICE

WILLIAM J. MILLER, OF SWISSVALE, PENNSYLVANIA

AUTOMATIC SAFETY DEVICE FOR POTTERY MACHINES

Application filed March 9, 1927, Serial No. 173,994. Renewed October 27, 1927.

My invention relates to improvements in pottery machines in general, and more particularly to such as described in my application for patent for mold conveying and pottery fabricating mechanisms, Serial No. 159,395, filed January 6, 1927, which has become Patent No. 1,697,993, dated Jan. 8, 1929.

One of the objects of my improvement is—
to prevent damage to the machine or any part
thereof, due to accidental stopping or over-
running of certain of the working parts of
the machine.

Another object of my improvement is—to
automatically discontinue the reciprocation
of the jiggers when the conveying mechanism
of the machine fails to function properly,
and also when the pressure between the pro-
files and the charge of material on the molds
becomes excessive.

Among other features, the machine in-
cludes instantly acting electrical devices to
automatically discontinue the said reciproc-
ation of the jiggers, and also a reliable me-
chanical device or mechanism for co-operat-
ing with said electrical devices and also to re-
place them, when they fail to function prop-
erly through some unforeseen cause, where-
by the functioning of the safety devices as a
whole is doubly assured and provided for.

A further object of my invention is—to
provide a means for discontinuing the rota-
tion of the shaft, which actuates the machine,
said means to be actuated by a departure
from normalcy in the operation of the ma-
chine, and said means to remain inactive when
the operation of the machine is normal.

A still further object of my improvement
is—to have my above automatic safety de-
vices for pottery machines simple, durable,
and inexpensive.

Other objects and advantages will herein-
after appear.

I attain these objects by the devices and
mechanisms, which are illustrated in the ac-
companying drawings, or by any mechanical
equivalent or obvious modification of the
same. The drawings illustrate the invention
applied to a machine wherein the jigger
mechanism is mounted on a movable or trav-
eling frame, but it will be obvious that the

invention may be applied to, and function in
connection with a machine wherein the jigger
mechanism is stationarily mounted, such for
example as the machine illustrated in my co-
pending application Serial No. 202,629, filed 55
June 30, 1927, for conveying mechanism.

In the drawings Fig. 1 is a fragmentary
plan view of the machine; and Fig. 2 is a side
view, looking from left to right in Fig. 1.
Fig. 3 is a detail on a larger scale of the ter- 60
minal and switch contact members and their
supports, which are hereinafter described.

Like numerals refer to like parts through-
out the several views:

11 designates vertical members of a mov- 65
able jigger frame 10 of a pottery machine,
such as described in my above noted patent,
and 12 a horizontally disposed cover frame,
which has thereon sockets 13, which are slid-
ably mounted on said members 11, for a pur- 70
pose, which is hereinafter described.

Oppositely extending spurs 14 and 15 are
shown as provided on some of said sockets 13.
Each of said spurs 14 has at the end thereof an
insulated terminal and switch contact mem- 75
ber 16, for connecting thereto electric wires *a*,
which lead to the electric motor 76. The mo-
tor 76 operates a shaft 30, which actuates the
reciprocation of the jigger spindles 27 of the
machine and the travel of the conveyor for 80
moving said jigger frame 10 of the above ma-
chine. Each of said spurs 15 has at the end
thereof an insulated terminal and switch con-
tact member 17, for connecting thereto elec- 85
tric wires *b*, which lead to an electro-magnetic
brake 75, to act on a disc 85 on said shaft 30.

Beams 18 are shown as secured to the upper
ends of some of the members 11, and they
have adjustably suspended therefrom, by
means of nuts 19 and safety nuts 20, vertical 90
rods 21.

A sleeve 22 is slidably mounted on each of
said rods 21 and supported in position by
means of a collar 23 thereunder, which is ad-
justably secured to each of said rods 21 by 95
means of a suitable set screw.

Said sleeves 22 may be kept from rotation
on said rods 21 by means of suitable keys or
splines therebetween, which are not shown in
the drawings.

Springs 86 are interposed between the underside of the beams 18 and the top of the sockets 13, thereunder, for a purpose, which is hereinafter described.

5 A collar 90 is shown in Fig. 1 as adjustably secured by means of a screw 92 to the upper end of each of the other members 11, which has no beam 18 thereon, and springs 86 are also interposed between the underside of said 10 collars 90 and the top of the sockets 13 thereunder, for a purpose which is hereinafter described.

The sleeve 22 has thereon a horizontal projection 24, which extends into the space between said spurs 14 and 15, and it has at 15 the end thereof an insulated terminal and switch contact member 25, for electric wires c, which lead to a source of electric power such as an electric generator or an electric main.

20 Each of the members 16, 17 and 25 has thereon a metal contact for electrically connecting said wires a, b and c to each other when any two of said contacts are brought into touch with each other.

25 When the machine is in operation the cover frame 12 is positioned above the ends of the mold carrying pallets 26, which are described more in detail in my above co-pending application. The wires c of the member 25 on 30 the projection 24 are electrically connected to the wires a of the terminal and switch contact members 16 on the spurs 14, thereby supplying current to the motor 76, which operates primarily to impart reciprocation to the jigger spindles 27, which have chucks 29 thereon, and movement to the jigger frame 10 of 35 the machine.

40 A compression spring 28 is interposed between the underside of each of the beams 18 and the top of the sleeves 22, for a purpose, which is hereinafter described.

45 Brackets 87, which have thereon sliding blocks 88, are mounted on the cover frame 12; said blocks 88 have adjustably secured there- to profiles 89.

The brackets 87, blocks 88 and profiles 89 normally operate substantially as described in my co-pending application for patent for Machine for use in the manufacture of pottery 50 ware, filed November 17, 1926, Serial No. 148,872.

When the motion of the travelling jigger frame 10 of the machine is accidentally either stopped, advanced or retarded with relation 55 to the pallets 26, the chucks 29 on the jigger spindles 27 are thereby brought out of registration with the pallets 26 and strike the underside of the same, thereby raising said pallets above their normal level, whereupon the 60 cover frame 12 with the sockets 13 thereon will be raised by the pallets 26, thereby raising the spurs 14 with the terminal and switch contact members 16 and wires a thereon out of contact with the terminal and switch contact member 25 and the wires c on the projec-

tion 24. The current will then be cut off from the motor 76.

The cover frame 12 with the sockets 13 thereon may also be raised by an excess of pressure between the profiles 89 and the material on molds 91, which are supported by the chucks 29 during the operation of profiling, thereby producing the same effect as the raising of the frame 12 by the pallets 26.

70 The springs 86 act to return the cover frame 12 to its original position after the cause of the said excess of pressure has been removed; they also serve to make the pressure between the profiles 89 and the material on said molds resilient.

75 The motor 76 may, however, continue to revolve by momentum, thereby causing the chucks 29 still further to raise the pallets 26 with the cover frame 12 thereover. This will cause a further rise of the sockets 13 with the spurs 15 thereon, thereby bringing the insulated terminal and switch contact members 17 with the wires b thereon into electrical connection with the wires c on the terminal and switch contact members 25 on the projections 90 24, whereby current may be supplied to an electromagnetic brake 75, which may be so positioned as to exert a retarding force on a disc 85, secured to the shaft 30, which is employed for reciprocating the spindles 27, 95 thereby quickly stopping the same.

80 Any further rise of the frame 12 by means of the chucks 29 will cause the spurs 15 to press on the projections 24 upwardly, thereby raising the sleeves 22 on the rods 21 against the force of the springs 28, which serve to maintain the contact between the members 25 and 17 and to prevent the fracture of the projections 24 or spurs 15.

85 The chucks 29 serve to intermittently raise 105 the molds 91 from the pallets 26, to bring them into operative position under the profiles 89, as described more in detail in my last mentioned co-pending application.

90 When the mold 91 happens to be misplaced, or when a higher mold is erroneously placed in position instead of a lower one, an excess of pressure will be produced between said mold and the profile 89, which will also cause the cover plate 12 to be raised, thereby bringing into action the above described means for disconnecting the motor 76 and applying the brake 75.

95 The shaft 30 operates to impart reciprocation to the jigger spindles 27 and motion 110 to the sprockets 31, which engage the chains 32 and advance the pallets 26, as is described in my above co-pending application.

100 The shaft 30 is actuated by the electric motor 76 in a way which is hereinafter more 115 fully described.

105 A clutch 33-34, which consists of two parts 33 and 34, is provided, for normally connecting the shaft 30 to the electric motor 76.

The part 33 of said clutch is in spline sliding engagement with the shaft 30, and the part 34 is swivelled on the same shaft.

A spring 35 is abutting at one end thereof against a collar 36, which is adjustably secured to the shaft 30 by means of a suitable set screw, and at the other end thereof against the rear of a sleeve 37, which is made in one with the part 33, thereby pressing said part 10 against the part 34, which is kept from longitudinal displacement on the shaft 30 by means of two collars 38 and 39, which are placed one on each side of the part 34 and are secured to the shaft 30 by means of suitable set screws as shown.

A stepped pulley 40 is formed on the part 34, for a belt, whereby it may be operatively connected to the motor 76, thereby actuating the shaft 30.

20 A forked yoke 41 is slidably engaged in a groove 42 in the sleeve 37; the latter rotates on the yoke 41, and may be shifted thereby on the shaft 30, whereby the part 33 may be moved out of contact with its counterpart 25 34, as is hereinafter described.

The yoke 41 is adjustably secured to the end of a horizontal rod 43 by means of nuts 44 and 45 on a threaded portion 46 on the rod 43.

30 A bell crank lever 47-48 is pivotally connected at its bend or elbow to the frame of the machine at 50 and has its vertical arm 47 operatively connected to the rod 43 by means of a bifurcation 56 at the end of the 35 arm 47, which bestrides the rod 43, and a collar 49, which is shown as adjustably secured to said rod at the left side of the bifurcation 56 in Fig. 2 of the drawings, by means of a suitable set screw. The collar 49 takes 40 up the thrust of the arm 47, to move the rod 43 in a direction to the left in Fig. 2 of the drawings, and it returns the arm 47 to its original position when said rod is moved in a direction to the right in Fig. 2 of the drawings under the influence of the spring 35, the sleeve 37 and the yoke 41.

The horizontal arm 48 of said crank lever is pivotally connected at 54 to the lower end of one section 51 of a vertically disposed connecting rod 51-52, which consists of two sections 51 and 52, which are adjustably connected to each other by means of a union 53, and suitable right and left threads at the adjacent ends of said sections.

55 The upper end of the section 52 is pivotally connected at 55 to the cover frame 12, as shown.

Any upward motion of the cover frame 12, as above described, will be transmitted 60 by means of the connecting rod 51-52 and the bell crank lever 47-48 to the collar 49 and rod 43, thereby moving the latter to the left in Fig. 2 of the drawings, thereby causing the yoke 41 to shift the sleeve 37 65 and part 33 of said clutch out of engage-

ment with the part 34 thereof, whereby the shaft 30 will be mechanically disconnected from the motor 76, which actuates the same.

The shifting of the sleeve 37 and part 33, as above mentioned, is done in opposition to the force of the spring 35, which causes the sleeve 37 to return to its original position when said cover frame 12 is allowed to descend, as when the machine is brought into normal condition again by the removal of the cause of the disarrangement; the sleeve 37 and yoke 41 then cause the rod 43 with the collar 49 thereon to move in a direction to the right in Fig. 2 of the drawings; the collar 49 is then kept by the influence of the spring 35 in contact with the bifurcation 56 on the arm 47 of the bell crank lever 47-48, when the latter is returned to its normal position by means of the weight of the frame 12 and the connecting rod 51-52.

80 The rod 43 or the arm 47, preferably the latter, may also be connected by means of a lever of the first class to a suitable belt shifter, to remove the belt from the stepped pulley 40, said shifter moving in a direction from left to right in Fig. 2 of the drawings when the rod 43 and arm 47 are moving in the opposite direction, to disconnect the clutch 33-34; the said shifter may be designed to work only in one direction, to wit: to throw the belt off of the pulley 40, without pulling the belt on to said pulley again.

85 The above means for disconnecting the motor from the shaft 30 by the removal of the belt from the stepped pulley 40 may be employed as an additional precaution in case some part of the above described clutch connecting means fails to function properly, as when the collar 49 may get loose on the shaft 30, also to prevent the premature restoration 90 of the connection of said shaft with the electric motor 76 by means of the weight of the frame 11, through the pressure of the spring 35, as hereinbefore described, or through any other cause.

100 A bracket 57, which terminates at its upper end in a suitable brake shoe 58, is secured to the frame of the machine by means of suitable fastenings as shown. Said shoe is positioned to intercept the part 33, when the latter is moved from right to left in the drawing, as hereinbefore described, to limit the travel of said part in that direction and also to engage the rear of said part and to act on it as a brake, whereby the rotary motion of the shaft 30, which may be produced by the momentum of the parts secured thereto, may be quickly stopped.

110 The brake shoe 58 may be replaced by a toothed member, if desired, to form a jaw 115 clutch with the rear of the part 33, which may also be provided with teeth, to mesh with said member.

120 The rod 43 is shown as adjustably connected to another rod 59, which is in line 130

therewith, by means of a union 60 and right and left threads on the contiguous ends of the rods 43 and 59, thereby forming one connecting rod of adjustable length, as shown.

5 The outer end of the rod 59 is pivotally connected at 61 to an oscillating arm 62, which is pivotally connected at the lower end thereof to a part 64 of the stationary frame 77 of the machine, which is described in my above co-pending application.

10 The upper part of the arm 62, as seen in Fig. 2 of the drawings, extends in front of a double contact switch plate 65, which is secured to a stationary part 78 of the machine, 15 and has mounted thereon a pair of insulated terminal and switch contact members 66, which have thereon wires c, which lead to a source of power, and suitable contacts, for electrically connecting said wires c to other wires, which are hereinafter described.

20 The switch plate 65 has thereon two pair of insulated terminal and switch contact members 67 and 68, one pair on each side of the arm 62, as shown in Fig. 2. The members 67 are secured to the switch plate 65. 25 The members 68 are slidably connected to stationary posts 79 on the plate 65 by means of extension stems 80 at the rear of the members 68 and sockets 81 in the posts 79.

30 Springs 82 are interposed between the posts 79 and the members 68, to keep the latter in position and to afford a resilient contact to said members with the members 66 on the arm 62 when the latter is moved to the 35 left in Fig. 2 of the drawings.

35 Nuts 83 on threaded portions 84 at the end of the stems 80 limit the motion of the members 68 to the right in Fig. 2 of the drawings under the influence of the springs 82.

40 The members 67 have thereon wires a, which lead to the motor 76; the members 68 have thereon wires b, which lead to the brake 75, which is hereinbefore described.

45 The members 67 and 68 have thereon also contacts, for electrically connecting the wires a and b to the wires c on the members 66.

50 It is evident that the motion of the rod 43 in a direction from right to left in Fig. 2 of the drawings will swing the arm 62 in a direction to bring the wires c into electrical connection with the wires b, thereby applying the electro-magnetic brake 75 to the shaft 30, and the motion of the rod 43 in the opposite direction will swing the arm 62 in the opposite direction, thereby electrically connecting the wires c with the wires a, after disconnecting the wires c from the wires b, thereby disconnecting the brake 75 and thereby starting the motor 76.

55 The said brake is also provided to act independently of and in addition to the commercial electric brake, which is supplied with certain standard motors and which acts to instantaneously arrest the revolution of the motor

when the electrical current, passing through the latter, is discontinued.

60 In this way an additional provision is made for stopping the motor 76 by the raising of the cover frame 12 by means of the chucks 29 on the spindles 27, in case the clutch 33-34 should fail to disengage the shaft 30 from the motor, and for starting the motor again by the lowering of the frame 12.

65 To prevent the over-running of the movable frame 10, which may be due to any failure of the means for disconnecting the same from the chain 32, as described in my above first mentioned copending application, or to any other cause, I provide an automatic electrical means for stopping the motor 76, which primarily controls the movement of the shaft 30, sprockets 31 and chains 32, thereby automatically discontinuing the tractive effort on the frame 10, which has a very slow motion 75 and an inappreciable momentum, and which is, therefore, readily brought to a standstill.

70 I also combine this automatic electrical means for stopping the motion of the frame 10 with the hereinbefore described mechanical means for automatically disconnecting the shaft 30 from the motor 76, thereby simultaneously discontinuing and stopping the reciprocation of the spindles 27.

75 The above automatic electrical means comprise a horizontally disposed bolt or member 70, which is adjustably connected to a flange 71 on the frame 10 by means of a nut 72, in contact with the flange 71, which is tapped, and a thread at one end of the member 70, which terminates at the other end thereof in a head 73, and is so positioned as to be intercepted by the upper end of the arm 62 when the frame 10 is over-running, thereby swinging the arm 62 on its pivot 63 from the position shown in Fig. 2 of the drawings to the left thereof on the switch plate 65, thereby breaking the contact of the members 66 and wires c thereon with the members 67 and wires a thereon and making a contact between the members 66 and the wires c thereon with said members 68 and wires b thereon, thereby disconnecting the motor 76 from the source of power and connecting the electromagnetic brake 75 thereto, thereby discontinuing the current in the motor 76 and thereby quickly stopping the shaft 30 with the sprockets 31 and the chains 32 until the derangement of the machine is corrected, whereupon the arm 62 may be manually swung to its original position, to reconnect the motor 76 to its source of power and re-start the machine.

80 105 110 115 120 125 The said swinging of the arm 62 by the bolt 70 to the left in the drawings also causes the rods 59 and 43, with the yoke 41 to move the sleeve 37 with the part 33 of the clutch 33-34 to the left in Fig. 2, thereby disconnecting the clutch 33-34 and thereby me- 130

chanically disconnecting the shaft 30 from the motor 76.

A handle 74 is provided at the upper end of the arm 62, for manually swinging the 5 same as above described.

The hereinbefore described means for preventing over-running of the movable frame 10 may also be employed for normally bringing said frame to a standstill, instead of the 15 means for disconnecting said frame from the chain 32, as described in my above first mentioned co-pending application, if desired.

The proper point for making and breaking the hereinbefore described contacts of my automatic safety devices for pottery machines, 15 as well as for applying the mechanical disconnecting means, which are hereinbefore described, may be controlled by regulating the sundry adjusting means of the various parts 20 of said safety devices, as hereinbefore described.

The electric motor 76 in my above automatic safety devices for pottery machines may be replaced by any other source of power, 25 such as a steam engine, a gas engine or a line shaft, and the hereinbefore described movable insulated terminal and switch contact members may be replaced by suitable stop valves for said gas and steam engines or with 30 belt shifters and clutch disconnecting means for said line shafts, in addition to the mechanical disconnecting means, which are hereinbefore described in detail.

Many other changes may be made in my 35 automatic safety devices for pottery machines, without departing from the main scope of my invention, and parts of my invention may be used without other parts.

I do not, therefore, restrict myself to the 40 details as shown and described; but I intend to include also all mechanical equivalents and obvious modifications of the same within the scope of my invention.

I claim as my invention, and desire to secure by Letters Patent:

1. A pottery machine including a plurality of mold carriers, reciprocating jigger mechanism adapted to cooperate with said carriers, means for conveying said carriers horizontally over said jigger mechanism, a movably mounted cover frame, a source of power, means associated with said cover frame for controlling said source of power, said means being adapted to render the source of power 50 inoperative when the cover frame is raised due to abnormal operation of said mechanism and/or said conveying means.

2. A pottery machine including a plurality of mold carriers, reciprocating jigger mechanism adapted to cooperate with said carriers, means for conveying said carriers horizontally over said jigger mechanism, a movably mounted cover frame adapted to be raised 55 upon a departure from normalcy in the operation of the machine, a source of power, a

brake, means associated with said cover frame for controlling the source of power and the brake, said means being so disposed as to render the source of power inoperative when the cover frame is initially raised and for applying said brake upon continued upward movement of the cover frame. 70

3. A pottery machine including a plurality of molds, means for conveying said molds, a movably mounted cover frame, a vertically reciprocable jigger so arranged as to normally raise said molds without disturbing the cover frame, a source of power for operating said jigger and said mold conveying means, and means on the cover frame for rendering said source of power inoperative when the cover frame is disturbed in the operation of the machine. 75

4. A pottery machine including a plurality of molds, means for conveying said molds, a movably mounted cover frame, a jigger for cooperating with said molds, a motor for operating said jigger and said conveying means, a clutch operatively connecting the motor with the jigger and mold conveying means, and switch and lever means rendered operative through movement of the cover frame for shutting off the power to said motor and for disengaging said clutch. 80

5. A pottery machine including a plurality of molds, means for conveying said molds, a movably mounted cover frame, reciprocable means for cooperating with said molds, a source of power for operating said reciprocable means and said conveying means, a magnetic brake, and switch and lever means associated with the cover frame for rendering the source of power inoperative and for applying said brake. 95

6. A pottery machine including a plurality of molds, a conveyor for said molds, a movably mounted cover frame associated with the molds, reciprocable means for cooperating with the molds, a motor for operating said reciprocable means and said conveyor, a drive shaft, a clutch operatively connecting the motor with the said shaft, a brake, and switch and lever means associated with the cover frame for disengaging the clutch, shutting off the power to the motor and applying the brake. 100

7. A pottery machine including a mold, means for conveying said mold, a profile, means for bringing said mold and profile into cooperative relationship, a source of power for said machine, and means for rendering said source of power inoperative upon the creation of an excessive pressure between the profile and the material in the mold. 115

8. In a pottery forming machine, the combination with a conveyor, of mold carriers mounted in series in said conveyor and having a plurality of molds disposed therein, fabricating mechanism mounted above the horizontal plane of movement of said carriers and 120

- reciprocating chucks mounted below said horizontal plane, a main drive shaft and a source of power normally having an operative connection with said shaft, switch and lever means, and means rendered operative through abnormal movement of said fabricating mechanism and/or said chucks for disconnecting said source of power from said shaft.
9. In a pottery forming machine, the combination with a conveyor, of mold carriers mounted in series in said conveyor, fabricating mechanism mounted above the horizontal plane of movement of said carriers and reciprocating chucks mounted below said horizontal plane, a main drive shaft and a source of power normally having an operative connection with said shaft, a brake, and means for automatically applying said brake, said means being rendered operative through abnormal movement of said fabricating mechanism and/or said chucks.
10. In a pottery forming machine, the combination with mold conveying and pottery fabricating mechanism, of means for actuating said mechanism including a drive shaft and a source of power normally having an operative connection with said shaft, a brake, and means rendered active through abnormal operation of said mechanism for disconnecting said shaft from said source and applying said brake.
11. In a pottery forming machine, the combination with one or a plurality of reciprocable and rotatable chucks, of means for reciprocating and rotating said chucks including a drive shaft and a source of power normally having an operative connection with said shaft, and means rendered operative through retarded or advanced reciprocation of said chucks for disconnecting said shaft from said source.
12. In a pottery forming machine, the combination with a plurality of reciprocable and rotatable chucks, of means for reciprocating and rotating said chucks including a drive shaft and a source of power normally having an operative connection with said shaft, a brake, and means rendered active through retarded or advanced reciprocation of said chucks for applying said brake.
13. A pottery forming machine comprising, in combination, a jigger frame, one or more reciprocating chucks to support molds with material thereon, one or more profiles thereover to shape said material, a shaft to actuate said machine and a source of power to operate said shaft, and a means for automatically disconnecting said shaft from said source, said means being so disposed as to be kept inactive by the normal operation of the machine and to be brought into action by a departure from normalcy in the operation of the machine.
14. A pottery forming machine comprising, in combination, a jigger frame, one or more reciprocating chucks to support molds with material thereon, fabricating mechanism mounted above said chucks and adapted to operate on said material, a shaft to actuate said machine, a motor to rotate said shaft and suitable electric conduits for connecting said motor to a source of electric energy, and a means for automatically disconnecting said motor from said source, said means being so disposed as to be kept inactive during the normal operation of the machine and to be brought into action by a departure from normalcy in the operation of the machine.
15. A pottery forming machine comprising, in combination, one or more jigger spindles with chucks thereon to support molds, fabricating mechanism mounted above said chucks, a shaft to actuate said machine and a source of power to operate said shaft, and a means for automatically disconnecting said shaft from said source, said means comprising a two-part friction clutch and a member operatively connected thereto and so disposed as to maintain the parts of the clutch in engagement during the normal operation of the machine and to disengage said parts upon a departure from normalcy in the operation of the machine.
16. A pottery forming machine comprising, in combination, one or more reciprocating jigger spindles with chucks thereon, a traveling mold carrier thereover, a shaft to actuate said spindles and a source of power to operate said shaft, and a means for automatically disconnecting said shaft from said source, said means being so disposed as to be actuated by the upward motion of said carrier when the latter is raised by said chucks in the event said chucks are out of registration with said carrier.
17. A pottery forming machine comprising, in combination, one or more reciprocating jigger spindles with chucks thereon, a movable jigger frame to carry said spindles, a traveling mold carrier positioned over said spindles, a shaft to actuate said spindles and a source of power to operate said shaft, and a means for automatically disconnecting said shaft from said source, said means being so disposed as to be actuated by the upward motion of said carrier when the latter is raised by the upward motion of said chucks in the event the latter are reciprocated out of registration with said carrier.
18. A pottery forming machine comprising, in combination, one or more reciprocating jigger spindles with chucks thereon, a movable jigger frame for carrying said spindles, a traveling mold carrier positioned over said spindles, a shaft for actuating said spindles and a source of power for said shaft, and a means for automatically disconnecting said shaft from said source, said means being

so disposed as to be actuated by the forward motion of said frame upon overrunning of the latter.

19. A pottery forming machine comprising, in combination, one or more reciprocating chucks, fabricating mechanism mounted over said chucks, a shaft to actuate said machine and a source of power to operate said shaft, a brake, and a means for automatically disconnecting said shaft from said source and applying said brake, said means comprising a two-part friction clutch and switch and/or lever means connected thereto and so disposed as to maintain the parts of the clutch in engagement during the normal operation of the machine and to disengage the parts upon a departure from normalcy in the operation of the machine and subsequently apply said brake.
20. 20. In a pottery forming machine, the combination with a plurality of mold carriers, of means for conveying said carriers, a movably mounted cover frame, a source of power, a brake, means associated with the cover frame for controlling the source of power and the brake, said means being so disposed as to render the source of power inoperative when the cover frame is initially raised and for applying said brake upon continued upward movement of the cover frame.
21. In a pottery forming machine, the combination with a plurality of mold carriers, of means for conveying said carriers, vertically reciprocating jigger mechanism adapted to normally operate in synchronism with said conveying means, a movably mounted cover frame disposed adjacent said mechanism and adapted to be moved in the event of abnormal operation and lack of synchronism of said conveying means and said jigger mechanism, a drive shaft, a source of power having a clutch connection with said shaft, a brake, and means adapted to be operated through movement of the cover frame for releasing the clutch and applying said brake.

WILLIAM J. MILLER.
